UNITED STATES PATENT OFFICE

JAY A. AURINGER, OF BYWOOD, UPPER DAREY, PENNSYLVANIA, ASSIGNOR TO GENERAL ELECTRIC COMPANY, A CORPORATION OF NEW YORK

ELECTRIC SWITCHING APPARATUS

Application filed January 5, 1929. Serial No. 330,647.

My invention relates to electric switching apparatus of that type in which the main circuit controlling switch forms a part of a movable structure provided with isolating contacts which in accordance with the position of the movable structure are adapted to engage cooperating isolating contacts on a fixed structure.

The object of my invention is the provision of a switch of this type having improved shutter mechanism for covering the contacts on the fixed structure which is simple in construction, positive and relatively quiet in operation, effective in the closed position against interference which might endanger the life of an ignorant or careless person and inexpensive to manufacture.

My invention will be better understood from the following description taken in connection with the accompanying drawing, and its scope will be pointed out in the appended claims.

Referring to the drawing, Fig. 1 is a perspective view of a truck panel switch involving my invention; Fig. 2 is a detail drawn to a larger scale of the shutter mechanism shown in Fig. 1; and Fig. 3 is a further detail drawn to a still larger scale.

The truck panel switch which I have chosen to illustrate my invention is shown comprising certain structural features which are common to switches of this type, namely, a fixed structure or housing having isolating switch contacts adapted to be permanently connected to the usual bus bars and feeders of the station and a movable structure or truck carrying the control panel and the main circuit interrupter, such for example as an oil switch, and having isolating contacts which when the truck is in its "in" or operative position engage the aforesaid isolating contacts of the housing. In the drawing I have shown the fixed structure or housing at 1 and the movable structure or truck at 2, both preferably constructed of fabricated steel. The latter is mounted on wheels 3 and is shown provided with an upper set of isolating contacts 4 arranged diagonally and a lower set of similar contacts 5 arranged horizontally. An oil switch, not shown, con-

trolled from the switch panel, also not shown, controls the circuit connection between these two sets of isolating contacts.

The rear portion of the housing is in the form of a closed compartment in which are mounted two sets of fixed isolating contacts 7 which align and are adapted to connect with the corresponding contacts of the truck. To avoid confusion in the drawing, but one of the contacts 7 is shown but it will be understood that the number and arrangement of these contacts are the same as contacts 4 and 5. The front portion of the housing is shown comprising the side plates 9, of which the one on the near side has been removed for clearness in illustration, the lower side plates 10, and the bottom plates 11 which form tracks upon which may run the wheels 3 of the truck. A window or opening in the front wall of the closed rear portion permits the contacts 4 and 5 to project into that portion and to engage the corresponding fixed contacts 7 when the movable structure is rolled into the fixed structure. To prevent any possibility of an attendant or other person coming in contact with the live contacts 7 when the truck is in a withdrawn or inoperative position, I have provided the shutters 12 which automatically close the window when the truck is withdrawn and which reopen in response to the inward movement of the truck. Each shutter 12 comprises two portions or members 13 and 14 pivotally connected to each other so as to fold one upon the other as shown more distinctly in Fig. 2. Member 14 is pivoted to the housing being shown mounted on pivot pin 15 at the side of the housing. The free edge of member 13 has projecting pins at the top and bottom on which are mounted rollers which run in the guides or tracks 16 and 17 respectively. That end of each track adjacent the shutter pivot bends forward slightly as shown at 19 in Fig. 2 for the purpose of giving the shutter an additional outward throw when it is moved to the full open position.

The operating mechanism for the shutter comprises the levers 22, shown as angle irons, pivoted at one end by bolt 23 to the respective side plates 10 and normally inclined so that

rollers 24 on opposite sides of the truck may engage the inward flanges 25 of the levers and swing the levers upwardly when the truck is rolled into the housing. In as much as the shutters and the operating mechanism are similar in construction on the two sides of the housing that on one side only will be described. Referring to Fig. 2, the lever 22 at that end thereof opposite its fulcrum 10 has the frame 27 supporting the inwardly extending pin 28 and has the upward extension 29 the purpose of which will be described later. Operating shaft 30, journalled at its respective ends in the bracket 31 and in plate 11 has secured to it the shutter engaging arm 32. This arm is slotted for a part of its length and engaging in the slot is the pin 33 fastened to shutter member 13. I arrange shaft 30 close to the sides of the housing and near 15 the pivot rod 15 of the shutter, thereby avoiding interference with the truck and facilitating the operation of the shutter, the members of which when swung to the open position, as indicated by dotted lines in Fig. 2, fold 20 snugly upon each other and lie close to the side plate 9. On the lower end of the shaft is the cam 35 which as shown more clearly 25 in Fig. 3 comprises a segment of cylinder having a spiral groove 36 formed therein which receives the pin 28. By this construction it will be seen that the movement of the lever 22 as a result of rolling the truck into and out of the housing turns the shaft 30 to open and close the shutter, the parts being 30 so constructed and related that when the truck is in its withdrawn position the shutters are tightly closed and when the truck is rolled into the housing the shutters are automatically opened to the full open position. This 35 opening movement, however, does not begin until the rear face of the truck has passed beyond the front edge of the side plates 9, thereby preventing a person from reaching in and coming in contact with the live contacts 40 7. The spiral groove 36 terminates at both its upper and lower ends in straight or axial portions. The straight portion at the upper end accommodates any over-travel of the operating pin 28 when raised by the rolling in 45 of the truck; the straight portion at the lower end serves to lock the shutters in the closed position, thereby preventing a person from pulling or prying open the shutters when the truck is withdrawn. Although the weight of 50 the levers 22 may in certain cases be found sufficient to insure the closing operation of the shutters I prefer to make this operation more positive and to this end I have applied the spring 38 which is compressed between 55 the extension 29 and the collar 39 fixed on shaft 30.

While I have described only one embodiment of my invention, I do not wish to be limited to the particular form shown and described as it will be apparent that many modi-

fications therein may be made without departing from the scope of my invention as set forth in the appended claims.

What I claim as new and desire to secure by Letters Patent of the United States, is:

1. A truck panel switch comprising fixed and movable structures having cooperating contacts secured respectively thereto, a shutter for the contacts of the fixed structure comprising a pair of members hinged to each other at their adjacent edges and mounted to extend in alinement over the contacts of the fixed structure or to fold upon each other at the side of the fixed structure, an operating shaft for said shutters, an arm on said shaft connected with one of said members, a member controlled by said movable structure, and an irreversible cam interconnecting said member and said shaft for operating said shaft. 70

2. A truck panel switch comprising a fixed structure having isolating contacts, a movable structure having cooperating isolating contacts, a shutter pivotally mounted at one side of the fixed structure, said shutter comprising two pivotally connected portions, a guide for one of said portions, a rotatable operating shaft adjacent the pivot mounting of the shutter, an arm on the shaft connected to said one portion, and irreversible cam operatively connected to said shaft and a pivoted member on the fixed structure controlled by the movable structure for operating said cam. 80

3. A truck panel switch comprising a fixed housing having isolating contacts, a truck having cooperating isolating contacts, shutters adapted to cover the contacts of the fixed housing, and operating means for the shutters, said means comprising a lever pivoted to the fixed housing and arranged in the path of movement of the truck, a rotatable shaft connected with one of the shutters, and a cam connection between the shaft and the lever. 100

4. A truck panel switch comprising a fixed housing having isolating contacts, a truck having cooperating isolating contacts, shutters adapted to cover the contacts of the fixed housing, and operating means for the shutters, said means comprising a lever pivoted to the fixed housing and arranged in the path of movement of the truck, a rotatable shaft having an arm connected with one of the shutters, and a cam on the shaft arranged to be engaged by a portion of said lever, said cam having a straight portion whereby when the shutters are in closed position they are locked in that position. 110

In witness whereof, I have hereunto set my hand this 2nd day of January, 1928.

JAY A. AURINGER.
